UNITED STATES PATENT OFFICE.

JOSEPH SZABO, OF NEW CASTLE, PENNSYLVANIA.

DIGGING IMPLEMENT.

Application filed November 22, 1921. Serial No. 516,965.

To all whom it may concern:

Be it known that I, JOSEPH SZABO, citizen of the United States, residing at New Castle, in the county of Lawrence and State of Pennsylvania, have invented certain new and useful Improvements in Digging Implements, of which the following is a specification.

This invention relates to digging implements such as spades, shovels or the like, and it has for a general object to provide an implement of this type having its blade angularly adjustable with respect to the handle.

A further object of the invention is to provide means permitting a quick movement of the blade when the latter is to be adjusted through a large arc.

For further comprehension of the invention, and of the objects and advantages thereof, reference will be had to the following description and accompanying drawings, and to the appended claims in which the various novel features of the invention are more particularly set forth.

Fig. 1 of the drawings is a longitudinal sectional view of a spade having the invention embodied therein, this view being taken on the line 1—1 of Fig. 2.

Fig. 2 is a longitudinal sectional view, taken on the line 2—2 of Fig. 1.

Fig. 3 is a perspective view.

Fig. 4 is a transverse vertical sectional view, taken on the line 4—4 of Fig. 1.

Fig. 5 is an enlarged fragmentary axial section, showing particularly the locking element of the blade adjusting means.

Fig. 6 is a detail sectional perspective view of the socket element shown in Fig. 5.

As here embodied my improved digging implement comprises a tubular handle element 10 which has its forward end partially closed as at 11, leaving a diminished rectangular opening from the sides of which a pair 40 of integral cheek-plates 12 project forwardly.

Extending transversely in the handle 10, just within the opening left in the end, is a worm pinion 14 which is provided with trunnion elements 15 engaged in the opposite sides of the handle. This worm pinion 14 meshes with a worm gear sector 16 journaled between the cheek-plates 12, on a pin 16', this gear 16 having a pair of parallel projecting tongues 17, 17' between which the rear end of the blade 18 is inserted, being secured thereto by rivets 19. The gear

16 is flattened on one side flush with the face of the tongue 17 as shown. A fixed pin 20 extends between the cheek-plates 12 and limits the movement of the blade 18 in one direction. The pinion 14 may be rotated by means of a suitable tool fitted on one of the projecting ends of the trunnion elements 15, thus adjusting the angle of the blade 18 with respect to the handle 10.

For use in case it is desired to make a large adjustment of the blade 18 means are provided whereby the pinion 14 can be moved bodily out of engagement with the gear 16. To this end the worm pinion 14 is mounted on the free ends of a pair of arms 23 which are pivoted on a transverse rod 24 in the handle 10, the trunnions 15 of the pinion 14 projecting through arcuate slots 10' in the handle 10, which slots extend concentric to the rod 24.

The pinion 14 has also connected thereto the forward ends of a pair of links 25 which extend rearwardly for a short distance through the handle 10 and connect to one end of a lever 26 whose opposite end projects through a longitudinal slot 27 in the handle, the lever 26 being fulcrumed between its ends on a transverse pin 28 fixed in the handle. This lever 26 has a diminished end piece 30 over which a hollow button 31 is slidably fitted. A coiled expansion spring 32, fitted in a recess in the button 31, normally urges the latter outward along the part 30, disengagement being prevented by a head 33 on the said part engaging an internal shoulder on the button 31.

Fixed on the handle 10 is a socket element 35 having a T-slot 36 leading into one side thereof and communicating with an opening in said socket element in which the button 31 is engaged, this opening having an interior enlarged socket portion 36' into which the enlarged inner end 37 of the button 31 is pressed by spring 32. The two parts of the T-slot 36 correspond in diameter to the shank and enlarged inner end of the button so that by pressing inwardly on the button the same can be passed through the slot 36, and the lever 26 swung to move the pinion 14 out of contact with the gear 16, the bottom of the socket element being slotted as at 36a to accommodate the lever. The blade 18 can then be swung to approximately the desired position and the lever 26 returned to its normal position, moving the pinion 14 back into engagement with the gear 16.

For doing heavy work, where it is desired to take the strain off the pinion 14, the blade may be adjusted to the position shown in Fig. 2, with the flattened side of the gear 16 5 engaging the stop pin 20.

Having thus described my invention what I claim as new and desire to protect by Letters Patent of the United States is as follows:

- 10 1. A digging implement comprising a hollow handle, a blade pivoted on one end thereof, a worm gear fixed to said blade coaxially thereto, a worm pinion in said handle engaging said worm gear, a pair of swingable arms in said handle having the worm pinion mounted on their free ends, a lever fulcrumed in the handle and having one end projecting exteriorly therefrom, link means connecting the opposite end of 15 said lever to said gear pinion, and locking means applied to the outer end of said lever.
- 20 2. A digging implement comprising a hollow handle presenting a pair of longitudinally extending cheek-plates at one end, a worm gear pivoted to and between said cheek-plates, a blade fixed to the said gear, a worm pinion mounted in the handle and engaging said worm gear, a pair of swingable arms in said handle having said worm 25 pinion mounted on their free ends, a lever fulcrumed in the handle and having one end 30

projecting through a slot therein, a pair of links connecting the opposite end of said lever to said gear pinion, and means applied to the outer end of said lever for locking the 35 same.

3. A digging implement comprising a hollow handle presenting a pair of longitudinally extending cheek-plates at one end, a worm gear pivoted to and between said 40 cheek-plates, a blade fixed to the said gear, a worm pinion mounted in the handle and engaging said worm gear, a pair of swingable arms in said handle having said worm pinion mounted on their free ends, a lever 45 fulcrumed in the handle and having one end projecting through a slot therein, a pair of links connecting the opposite end of said lever to said gear pinion, and means applied to the outer end of said lever for locking the 50 same, said means comprising a sleeve slideable on said lever, and a socket element on said handle in which said sleeve engages, said socket element having a slot formed in one side thereof to permit of said sleeve and 55 lever passing laterally therethrough after an initial longitudinal movement of said sleeve on said lever.

In testimony whereof I have affixed my signature.

JOSEPH SZABO.
